UNITED STATES PATENT OFFICE.

JACOB F. LANDIS, OF HARRISBURG, PENNSYLVANIA.

IMPROVEMENT IN EGG BEATERS AND MIXERS.

Specification forming part of Letters Patent No. 151,784, dated June 9, 1874; application filed February 27, 1874.

To all whom it may concern:

Be it known that I, JACOB F. LANDIS, of Harrisburg, Dauphin county, Pennsylvania, have invented an Improvement in Egg Beaters and Mixers; and I do hereby declare the following to be a full and correct description of the same, reference being had to the accompanying drawings, in which—

Figure 1 is an end view. Fig. 2 is a cross-sectional view; and Fig. 3 is a longitudinal sectional view, taken through xy , Fig. 2; and Fig. 4 is a view of the scraper.

My invention relates to a machine for beating eggs, either in large or small quantities, and also for agitating and mixing other ingredients for culinary purposes.

My invention consists in placing within a suitably-shaped vessel a revolving shaft, having radial arms. These arms in their revolution pass between bars projecting from a longitudinal bar, running parallel with the revolving shaft.

A solid scraper may be inserted in the shaft, which, in its revolution, will clear the vessel of its contents.

In the drawings, A represent the vessel, resting upon suitable legs, and B its lid. Within this vessel, which is cylindrical in the bottom, is a shaft, C, revolving in the bearings c and c' . The bearing c' is made rigid with the shaft; but the bearing c enters the hollow portion of the shaft C, and is secured therein by the pin b . Extending from the surface of the shaft C, in four or more directions, are radial arms or beaters a , the ends of which in their revolution pass near the bottom of the vessel A. Extending from one end of the vessel A to the other is a cross-piece, D, from the bottom side of which drop the bars e , so arranged that the bars a on the shaft C in their revolution pass between them, and clear them of any adhering material.

To clear the vessel A of its beaten or mixed contents I place in holes i the legs i of the scraper I, one revolution of which raises the material from the bottom of the vessel, and facilitates its removal from the vessel.

To produce a rapid motion to the arms or beaters a I place upon the outer end of the bearing c the pinion n , which engages the cog-wheel m , which may be relatively much larger than the pinion n . A crank, k , upon the shaft of the wheel m , will supply the necessary power.

The operation of my machine is as follows: Power being applied to the crank k the shaft C is caused to revolve, and the arms or beaters a pass rapidly through any material which may have been placed into the vessel A, violently agitating it and mixing it. The bars e being placed between the paths of the arms a , clear them of adhering matter, and prevent the mass, also, in the vessel from revolving with the beaters.

With my machine I can first beat the eggs necessary for a cake, and then add each ingredient in its turn, and finally, by means of the scraper I, turn it all out, thoroughly mixed, ready for the oven.

What I claim, and desire to secure by Letters Patent, is—

In an egg-beater, constructed substantially as described, a revolving shaft and case, A, in combination with a horizontally-revolving scraper.

The above specification of my said invention signed and witnessed at Washington this 20th day of February, A. D. 1874.

JACOB F. LANDIS.
